UNITED STATES PATENT OFFICE.

HENRY S. YOUNG, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING APPARATUS.

Application filed October 6, 1923. Serial No. 666,948.

My invention relates to railway signaling apparatus.

I will describe one form and arrangement of signaling apparatus embodying my invention, and will then point out the novel features thereof in claims.

In the accompanying drawings, Fig. 1 is a diagrammatic view showing one form of railway signaling apparatus embodying my invention. Fig. 2 is a detail view illustrating, on a large scale, one of the signal units shown in Fig. 1.

Referring to this drawing, the reference characters 1 and 1^a designate the track rails of a railway over which traffic normally moves in the direction of the arrow. These track rails are divided by means of insulated joints 2 into a plurality of successive track sections A—B, B—C, C—D, etc.

Each such track section is provided with a track battery designated by the reference character E with an exponent corresponding to the location and connected across the rails adjacent the exit end of the section. Interposed between each battery E and one rail 1^a of the associated section is a resistance 4 one function of which is to limit the output of the battery when its terminals are short-circuited by the wheels and axles of a passing train. Each track section is also provided with a track relay designated by the reference character T with an exponent corresponding to the location and connected across the track rails adjacent the entrance end of the section. Each track section is thus provided with a track circuit comprising a battery E, a track relay T, a resistor 4 and the rails 1 and 1^a of the section in series.

Each section is also provided with a signal located adjacent the entrance end of the associated section, and designated by the reference character S with an exponent corresponding to the location. As here shown each signal comprises four light units, G, Y, Y' and R, each of which is provided with two electric lamps 50 and 50^a connected in parallel as shown in Fig. 2. The unit G is provided with a green lens so disposed that when the associated lamps are energized a beam of green light will be projected from the signal. Units Y and Y' are each provided with a yellow lens adapted, when

the associated lamps are energized, to project a beam of yellow light. Unit R is provided with a red lens adapted when the lamps associated therewith are energized to project a beam of red light. The signals therefore are capable of displaying various indications to the engineman in charge of trains moving over the stretch of track governed by these signals depending upon which unit or group of units is energized. Thus when the green unit is energized the signal displays a "proceed" signal meaning "proceed at authorized speed", when unit G and Y' are energized the signal displays an "alert" signal meaning "proceed prepared to pass next signal at restricted speed", when unit Y' is energized the signal displays a caution indication meaning "proceed prepared to stop at next signal", when units R and Y are energized the signal displays a "permissive" indication meaning "stop, then proceed at low speed", and when unit R is energized the signal displays a stop indication meaning "stop". Wherever in the following specification and claims I refer to a unit as a red unit, a yellow unit or a green unit as descriptive of unit R, Y, or Y', or G, respectively, it shall be understood that the color refers to the color of the associated lens and not to the unit itself.

Associated with each track relay T is a three-position relay which I will herein-after, for sake of convenience, term a "line" relay and which is here designated by the reference character K with an exponent corresponding to the location. Associated with each track relay T are also a light out relay and a pole changing relay designated by the reference characters L and J, respectively, with exponents corresponding to the locations.

Each section is also provided with a line transformer designated by the reference character F with an exponent corresponding to the location and having its primary winding constantly supplied with alternating current from a suitable source, as an alternator M, over line wires 3 and 3^a.

Each line relay K comprises two windings 29 and 30. Winding 29 is constantly supplied with alternating current by being connected across the secondary of the adjacent

line transformer as will be obvious from the drawing. Referring particularly to relay K^B , for example, the winding 30 of this relay is provided with a circuit which is controlled by track relay T^C and pole changing relay J^C . When relay J^C is de-energized, as shown in the drawing, this circuit passes from the secondary of transformer F^C , through wires 5 and 51, back 10 point of contact 32 of relay J^C , wire 38, front point of contact 37 of track relay T^C , wire 36, winding 30 of relay K^B , wire 35, front point of contact 34 of relay T^C , wire 33, back point of contact 31, and wire 11 back 15 to transformer F^C . Current of what I shall term "reverse relative polarity" is then supplied to a winding 30 and contacts 26 and 19 of this relay are then swung to the left. When relay J^C is energized the circuit for 20 winding 30 is the same except that this winding is then connected with the secondary of transformer F^C in the opposite direction so that current of what I shall term "normal relative polarity" is supplied to the winding. 25 Contacts 26 and 19 are then swung toward the right. When relay T^C is de-energized, the supply of current to winding 30 of relay K^B is completely discontinued, and contacts 26 and 19 assume an intermediate position.

30 Referring particularly now to signal S^D , the red unit R of this signal is provided with a circuit which passes from the secondary of transformer F^D through wires 5 and 6, winding of relay L^D , wire 7, back contact 8 of track relay T^D , wire 9, red unit R of signal S^D , and wires 10 and 11 back to transformer F^D . A low capacity fuse 6^a is inserted in wire 6. This circuit is closed only when relay T^D is de-energized under which condition the signal S^D will display a stop indication. The relay L^D is so designed that if both lamps associated with unit R are lighted, it will be closed, whereas, if either one of these lamps is burned out, this relay 45 will be open. If the lamps in unit R become short-circuited thus extinguishing the lamps, the excessive current burns out fuse 6^a which allows relay L^D to become de-energized. Assuming now that both lamps of unit R are 50 lighted, relay L^D is closed and closes over its front contact, a circuit for unit Y which passes from the secondary of transformer F^D , through wires 5 and 12, back contact 13 of track relay T^D , wire 14, front contact 55 15 of relay L^D , wire 16, yellow unit Y of signal S^D and wires 10 and 11 back to transformer F^D , thus causing signal S^D to display a permissive indication. It will be clear that with this arrangement if a per- 60 missive indication is being displayed and one of the lamps in the red unit R becomes ineffective as by burning out, or by short-circuit, yellow unit Y is immediately de-energized. In the absence of this protective 65 feature the greater intensity of the yellow

unit might cause an observer to mistake the permissive indication for a caution indication.

Referring now to signal S^B , yellow unit Y' is provided with a circuit which passes from the secondary of transformer F^B , through wires 5 and 6, winding of relay L^B , wires 7, front contact 8 of track relay T^B , wires 17 and 18, reverse contact 19 of line relay K^B , wires 20 and 21, yellow unit Y' 70 of signal S^B , and wires 10 and 11 back to transformer F^B . When this circuit is closed unit Y' is energized and if both the lamps associated therewith are lighted, relay L^B is energized thereby closing a circuit for green unit G and current flows from secondary of transformer F^B through wires 5 and 12, front contact 13 of track relay T^B , wires 92 and 23, front contact 24 of relay L^B , wire 80 25, reverse contact 26 of line relay K^B , wire 27, unit G of signal S^B , and wires 10 and 11 back to transformer F^B , thus causing signal S^B to display an alert indication. At the same time current flows through a branch 85 from wire 27 through winding of pole changing relay J^B , and wire 28 back to wire 11 thereby energizing this relay. It is therefore clear that relay J^B will be energized only when green unit G of signal S^B is energized.

It should be particularly noted that if a signal is displaying an alert indication (see signal S^B) failure of one of the lamps in the yellow unit Y' , which might result, in the absence of preventing means, in mistaking the indication for a proceed signal, causes the de-energization of the associated light out relay L and hence de-energizes the associated green unit G so that the signal gives a "caution" indication. It will, then, be 105 clear that under no possible circumstances can the failure of a lamp in the present system result in the displaying of a less restrictive signal indication than should be displayed.

The circuit traced above for yellow unit Y' of signal S^B is provided with a branch which passes from wire 17, through back contact 22 of relay J^B , and back to wire 21. It is clear that the circuit is closed through 115 this branch only when relay T^B is energized and relay J^B is de-energized, under which conditions unit Y' is energized and the signal displays a caution indication. (See signal S^C .)

The green unit G of each signal is also provided with another circuit which, as best shown in connection with signal S^A , passes from the secondary of transformer F^A , through wires 5 and 12, front contact 13 of track relay T^A , wires 22 and 29, normal contact 26 of line relay K^A , wire 27, unit G of signal S^A , and wires 10 and 11, back to transformer F^A . When this circuit is closed 125 unit G is energized and the signal displays 130

a proceed indication. It will be noted that when unit G of signal S^A is energized over this circuit the associated pole changing relay J^A is simultaneously energized exactly 5 as explained in relation to the circuits for the alert indication.

As shown in the drawing the section to the right of point D is occupied by a train 10 designated by the reference character Z.

10 Track relay T^D is therefore de-energized so that relay J^D is likewise de-energized and unit R of signal S^D is lighted through back contact 8 of relay T^D, thereby energizing relay L^D which in turn closes the circuit for yellow 15 unit Y, so that signal S^D displays a permissive indication. The de-energization of relay T^D causes relay K^C to be de-energized, but track relay T^C is energized, and signal S^C therefore displays a caution indication, 20 yellow unit Y' being energized through back contact 22 of relay J^C. Due to the de-energization of relay J^C, current of reverse relative polarity is supplied to relay K^B which becomes energized, closing 25 its reverse contacts. The resulting energization of yellow unit Y' of signal S^B causes relay L^B to become energized thereby closing the circuit for green unit G and relay J^B, both of which elements 30 thereupon becoming energized. Signal S^B now displays an alert indication. Since relays T^B and J^B are both energized, relay K^A is energized by current of normal relative polarity and green unit G of signal S^A 35 is energized, thus causing the signal to display a proceed indication. It will be noted that the proceed circuits for green unit G does not include light out relay L^A, and so this relay is de-energized.

40 Although I have herein shown and described only one form and arrangement of apparatus embodying my invention, it is understood that various changes and modifications may be made therein within the 45 scope of the appended claims without departing from the spirit and scope of my invention.

Having thus described my invention, what I claim is:

50 1. In combination, a section of railway track, a track relay for said section, a line relay for said section responsive to traffic conditions in advance, a signal comprising two light units, means controlled by said track relay and said line relay for energizing one of said units, controlling means in circuit with such unit, and means controlled by said means and said track relay for energizing the second said unit.

60 2. In combination, a section of railway track, a track relay for said section, a line relay for said section responsive to traffic conditions in advance, a signal comprising two light units, means controlled by said track relay and said line relay for energizing

one of said units, controlling means in circuit with such unit, and means controlled by said means, said track relay and said line relay for energizing the second said unit.

3. In combination, a forward and a rear section of railway track, a line relay for said rear section responsive to traffic conditions in said forward section, a second relay, a signal for said rear section comprising two units, a circuit including one of said units 75 and said second relay in parallel, and means controlled by said line relay and means including said second relay for controlling the second said unit.

4. In combination, a section of railway 80 track, a track relay for said section, a line relay for said section controlled by traffic conditions in advance, a third relay and a fourth relay for said section, a signal comprising two units, an electrical circuit including in parallel a contact of said line relay and a contact of said fourth relay, a contact of said track relay the winding of said third relay, and one of said signal units, and a second electrical circuit including in parallel the second unit of said signal and the winding of said fourth relay, a contact of said line relay, a contact of said track relay and a contact of said third relay.

5. In combination, a section of railway 95 track, a track relay for said section, a line relay for said section arranged to be energized in one direction or the other in accordance with traffic conditions in advance of said section, a third relay and a fourth relay 100 for said section, a signal comprising a green light unit and a yellow light unit; an electrical circuit including in parallel a reverse contact of said line relay and a back contact of said fourth relay, a front contact of said track relay, the winding of said third relay, and the yellow unit of said signal; and a second electrical circuit including in parallel the green unit of said signal, and the winding of said fourth relay, a reverse contact of said line relay, and a front contact of said track relay this circuit being provided with a branch which omits said reverse contact on the line relay and said front contact on said third relay but includes a 110 normal contact on said line relay.

6. In combination, a plurality of successive sections of railway track each provided with a signal, a line relay for each said section, a track relay for each said section, a 120 third relay for each said section, an electrical circuit for each section controlled by the associated track relay and including the associated signal and said third relay in parallel, and means controlled by each said 125 third relay and said track relay for supplying current to the line relay associated with the section next in rear.

7. In combination, a plurality of successive sections of railway track each provided 130

with a signal having two units, a track relay, a line relay, and a third and a fourth relay for each section, means for simultaneously energizing said fourth relay and one of said units; an electrical circuit for each section controlled by the associated track relay, line relay and fourth relay, and including the second unit of said signal and said third relay in parallel; and means controlled by each said third relay and said track relay for supplying current to the line relay associated with the section next in rear.

8. In combination, a plurality of suc-

sive sections of railway track each provided with a signal, a track relay, a line relay and a third relay for each section, a fourth relay for each section controlled by traffic conditions in advance; an electrical circuit for each section controlled by the associated track relay, line relay and fourth relay; and means controlled by each said third relay and said track relay for supplying current to the line relay associated with the section next in rear.

In testimony whereof I affix my signature.

HENRY S. YOUNG.
